CLAIM

The ornamental design for a shoe sole, as shown and described.

DESCRIPTION

FIG. 1 is a perspective view of a shoe sole showing my new design;

FIG. 2 is a bottom view thereof;

FIG. 3 is a left-side view thereof;

FIG. 4 is a right-side view thereof;

FIG. 5 is a front view thereof;

FIG. 6 is a rear view thereof;

FIG. 7 is an enlarged bottom view of an isolated tread element of FIG. 2 without the rest of the shoe sole;

FIG. 8 is a left side view thereof;

FIG. 9 is a right-side view thereof; and,

FIG. 10 is a perspective view thereof.

The broken lines show parts of the shoe sole and environment that form no part of the claimed design. The broken lines in FIGS. 7-10 show and area of enlargement and the broken lines form no part of the claimed design.

1 Claim, 10 Drawing Sheets
